Edward K. Warren

UNITED STATES PATENT OFFICE.

EDWARD K. WARREN, OF THREE OAKS, MICHIGAN.

STIFFENING-STRIP AND MODE OF PRODUCING THE SAME.

SPECIFICATION forming part of Letters Patent No. 311,621, dated February 3, 1885.

Application filed April 25, 1884. (No model.)

To all whom it may concern:

Be it known that I, EDWARD K. WARREN, residing at Three Oaks, in the county of Berrien and State of Michigan, and a citizen of the United States, have invented certain new and useful Improvements in Stiffening-Strips and Mode of Producing the Same, of which the following is a full description, reference being had to the accompanying drawings, in

10 which—

Figure 1 is a section of a single strand; Fig. 2, a section of a completed strip; Fig. 3, a section of a wound strip, and Fig. 4 a cross-section.

15 The object of this invention is to produce an improved article of manufacture by the use of the enamel or quill portion of feathers in the flat form, and to so secure the parts together that they will not become separated in use, by the unraveling of the covering or by the breaking or wearing through of the covering; and its nature consists in first forming 20 strands of this material, then placing the strands side by side, and then covering them by 25 cross-winding and stitching between the seams, as is hereinafter more fully described.

In the drawings, *a* indicates the strand; *b*, *c*, covering threads or parts, and *d* the stitching-lines.

30 This invention is an improvement upon that secured to me by Letters Patent No. 286,749, and the separate construction of the strands as is there shown and described—that is to say, I take the enamel or quill portion 35 of feathers, which has heretofore been waste material, and split or separate the same into fine strips or fibers, which strips may include a portion or all of the quill part of the feathers, as may be desired. These are wound by 40 a covering of thread, small cord, or wire, in a round form, as shown in my former patent. I take two or more of these strands (four being shown) and place them side by side, and 45 unite them by an additional winding, *b*, *c*, which in its best form is made by cross-winding—that is, winding the thread or wire *b* in one direction and the thread or wire *c* in an opposite direction, somewhat after the manner, but without the interlacing, of braiding; 50 but these threads may have the braiding interlacing, if desired. This covering is applied by suitable machinery for that purpose, and after the covering has been applied, or during

the process of its application, I stitch the covering along and between each of these strands with a lock-stitch, so as to firmly interlock the covering with the strands, and I thereby prevent its raveling or disintegration by breaking or cutting. This stitching can be applied after the covering is completed by an ordinary lock-stitch sewing-machine; but in practice it will be desirable to apply the stitching more rapidly, and I propose hereafter to construct machinery for such purpose.

55 By this method of proceeding I produce a firm flat strip of this material, which I have termed "feather-bone," which can be formed into uniform lengths or into any desired length, and which is adapted to be used in nearly all of the places where whalebone has 60 heretofore been used, and is also adapted to additional uses. It is flexible, strong, durable, and less liable to break than whalebone, and is much more elastic, flexible, and durable than the whalebone or materials which have 65 heretofore been used as substitutes for whalebone—such as strips of brass, steel, cord, and 70 tampico, or other similar articles. This completed article can be cut without raveling or 75 injury to the fiber of the strands at any point 80 along its length, and it is for this reason especially adapted to be made in rolls or lengths for the trade.

85 What I claim as new, and desire to secure by Letters Patent, is as follows:

1. As an improved article of manufacture, the flat strip composed of two or more strands of feather-bone cord, made from the enamel or quill portions of feathers, said strands lying side by side and being secured together by 90 cross-winding threads and threads passing lengthwise between the strands and through the braid, substantially as specified.

2. The method of forming flat strips composed of previously-wound strands, consisting in cross-winding two or more strands placed side by side, substantially as described, with binding-threads to form a flat strip, and afterward stitching through and through the strip lengthwise thereof and between all of the 95 strands, substantially as described.

EDWARD K. WARREN.
